UNITED STATES PATENT OFFICE.

FREDERICK W. ATWELL, OF ANTIOCH, ILLINOIS.

TOY.

1,084,122.

Specification of Letters Patent.

Patented Jan. 13, 1914.

Application filed April 4, 1913. Serial No. 758,879.

To all whom it may concern:

Be it known that I, FREDERICK W. ATWELL, a citizen of the United States, residing at Antioch, in the county of Lake, State of Illinois, have invented certain new and useful Improvements in Toys; and I do hereby declare the following to be a full, clear, and exact description of the invention, such as will enable others skilled in the art to which it appertains to make and use the same.

This invention relates to toys, and has for its object to so construct a device of this character that the figures will simulate, during their travel, tumbling acrobats.

A further object of the invention is to provide a toy of this type, which is extremely simple to operate, and one which when operating will cause constant amusement.

20. With these and other objects in view, this invention resides in the novel features of construction, formation, combination and arrangement of parts to be hereinafter more fully described, claimed and illustrated in the accompanying drawing, in which:—

Figure 1 is a side elevation of the toy. Fig. 2 is a top plan view of the same. Fig. 3 is an end view. Fig. 4 is a vertical sectional view, partly in section.

30. Referring to the drawing, the numeral 1 designates a base, the same being circular in shape and is formed centrally with a socket 2 in which is mounted the tenon 3, formed upon the lower end of the vertically disposed post 4. Rotatably mounted upon the upper end of the post 4 is a gear 5, the same being provided with an operating handle 6.

The post 4 is provided intermediate its ends with an annular groove 7, having slidably engaged therein a band 8, said band being provided with a lug 9, and to which is rotatably connected the inner end of the shaft 10. Keyed to the shaft 10 and adjacent its inner end is a gear wheel 11, which is adapted to mesh with the gear 5, and also with the sheet metal gear band 12, which is mounted upon the base 1 so that when the gear 5 is rotated the gear wheel 11 will, during its rotation, travel around the gear band 12, during which time the shaft 10 is rotated and the band 8 is sliding in the groove 7.

Fixed to the outer end of the shaft 10 is a disk 13, the outer face of which is provided with a central lug 14, and to which is pivotally connected the inner ends of the arms 15,

said arms having their outer ends provided with lateral extensions 16, which pivotally engage the bodies of the figures 17. The figures 17 are provided with jointed arms and legs, so that during the travel of the 60 same their antics will be comical.

Formed upon the outer end of the disk 13 are pins 18, said pins being spaced, and disposed in diagonal relation so that during rotation of the disk one of the pins will engage one of the arms 15 and swing the same upwardly until it reaches a perpendicular position, after which it will swing downwardly while the other arm is being engaged by the other pin and being swung upwardly until the same reaches a perpendicular position, after which said arm will swing downwardly, thus imparting rotary movement to the figures 17.

What is claimed:—

1. A toy comprising a base, a post supported upon the base, a shaft rotatably connected to the post, arms pivotally connected at their inner ends to the shaft, figures pivotally connected to the arms, means supported by the shaft for successively engaging the arms to impart swinging movement thereto, means for causing the shaft to rotate around the post, said means also serving to impart axial rotation to the shaft, as and for the 85 purpose set forth.

2. A toy comprising a base, a post rising from the base, a band slidably connected to the post, a shaft rotatably connected to the band, a gear wheel rotatably mounted upon 90 the upper end of the post, a band gear mounted upon the base, a gear wheel fixed to the shaft and adapted to mesh with the first named gear and band gear, a disk carried by the outer end of the shaft, a lug carried by 95 the disk, arms having their inner ends pivotally connected to the lug, figures pivotally connected to the outer ends of said arms, spaced pins carried by the disk for successively engaging the arms to impart swinging 100 movement thereto, and means for rotating the first named gear to cause the second named gear to travel upon the band gear.

In testimony whereof, I affix my signature, in the presence of two witnesses.

FREDERICK W. ATWELL.
